UNITED STATES PATENT OFFICE.

PETER JOHN KURSCHEIDT, OF WOODHAVEN, AND HARRY E. NORWOOD, OF BROOKLYN, NEW YORK.

CLUTCH FOR WINDOW REGULATORS.

Original application filed April 29, 1922, Serial No. 557,470. Divided and this application filed April 28, 1926. Serial No. 105,061.

Our invention relates to window regulators adapted to raise or lower a window upon rotation in the proper direction of a rotatable crank or handle which is mounted on the device and operatively connected with the operating mechanism.

It is a particular object of the invention to provide a window actuating mechanism which can be operated with a minimum of effort from an operating shaft but which will be held positively in any position to which it may have been adjusted.

Other objects of the invention relate to the production of a window regulator of simplicity of construction and of ease of operation, the invention consisting in the novel parts and combinations thereof hereinafter more particularly described and then specified in the claims:

20 In the accompanying drawing illustrating a practical embodiment of the invention:

Fig. 1 is a front elevation of the window regulator.

25 Fig. 2 is a front elevation of the upper portion of the device on the line 2—2 of Fig. 3.

Fig. 3 is a section taken through the upper portion of the device.

30 Fig. 4 is a side elevation of the crank shaft.

Fig. 5 is an end view thereof.

Fig. 6 is a front elevation of the clutch driving member.

Fig. 7 is a front elevation of the driven member.

35 Referring in detail to the several figures of the drawing:

1 indicates a window which is adapted to be reciprocated vertically in a suitable frame, the lower part of which is indicated at 2.

40 3 indicates a plate which is mounted on and secured to the lower part 2 in any desirable manner while 4 indicates a cover plate which is screwed to said plate by suitable screws

45 5 and which forms with said plate 3 a housing containing a clutch and other mechanism to be presently described. A vertical depending bar or strap 6 is fastened at its upper end to the plate 3 and at its lower end to a cross-bar 7 which is detachably secured to

50 the side walls of other parts of the window well.

An endless driving chain 27 passes over an upper sprocket 28, which is mounted on the plate 3 and a lower sprocket 20 support-

ed on the bar 6. The chain 27 is connected to the window 1 by means of a roller stud 29 engaging in a slot of a plate 30 which is secured to and depends from the lower side of the window. A handle 31 is mounted on a housing and connected with mechanism within said housing formed by the cover plate 4 and plate 3 whereby rotation of said handle will rotate the upper sprocket 28, thereby causing the chain 27 to travel around the upper and lower sprockets thus effecting a raising and lowering of the window depending on the direction of rotation given to the handle.

32 indicates a crank shaft which is provided with hub portions 33 and 34 rotatably received by an annular neck 35 pressed out from the plate 4 and a removable bearing 36, respectively, the bearing being received and held within an opening in the plate 3 (see Fig. 3). The handle or crank 31 is secured to the end of said shaft 32 in any desirable manner. The shaft is provided with a substantially rectangularly shaped driving member actuator 37 preferably integral therewith and having flat sides and rounded ends and also end flanges 38 slidably fitting intermediate the plate 4 and the driving member 42 referred to below. The flanges 38 act to prevent rocking or displacement of the clutch parts.

85 The fixed clutch member 39 is provided with pins 40 extending through depressions in the plate 4 the ends of said pins being riveted over on said plate within said depressions, whereby the clutch member is securely held against movement. Said clutch member is also provided with an enlarged opening 41 extending therethrough having a serrated or toothed inner edge as indicated.

90 The driving member of the clutch is indicated at 42 and is provided with outwardly projecting pins 43 and an opening 44 having an upper flat wall 44^a, rounded side walls 44^b and a lower wall 44^c having a stop or cam surface 44^d (see Fig. 6). The lower portion of the driving member is also provided with teeth 45 adapted to interfit with the teeth of the opening 41 of the fixed member 39. The opening 44 is adapted to receive the actuator 37 on the shaft 32 and the opening 41 of the fixed clutch member 39 receives the driving member 42, the fixed clutch mem-

ber and driving member 42 lying in the same plane. When the handle or crank on the shaft 32 is not being operated one of the flat sides of the actuator 37 engages the upper 5 flat wall 44^a of the opening 44 while its curved ends engage the rounded side walls of said opening as shown in Fig. 2.

The driven member indicated at 46 is loosely carried on the shaft and comprises a 10 flat disk provided with slots 47 therein slidably receiving the pins 43 of the driving member 42. One of said slots carries a spring 48 bearing against one of the pins 43 and acts to retain the driving member 42 in the position shown in Fig. 2 with its teeth 45 in locked engagement with the teeth of the fixed member 39, whereby rotation of the shaft 32 will be prevented if rotation is attempted from the driven member 46 as will 15 be readily understood.

The driven member 46 is provided with outwardly projecting pins 49 entering and interfitting with suitable openings in a pinion 50 loosely mounted on the shaft, said 20 pinion meshing with a large gear 51. When the crank or handle is rotated the element 37 takes the position shown in Fig. 6 or at right angles to said position depending on the direction of rotation of the crank or 25 handle. As the element 37 may not completely rotate within the opening 44 it forces the driving member, against the action of the spring 48, to move in a direction whereby the teeth 45 will become disengaged from the teeth of the fixed member 39 after which the member 42 will rotate with the shaft. Rotation of the shaft thus 30 effects a rotation of the driven member 46 due to the pins 43 engaging in the slots 47. 35 When the driven member rotates the pinion 50 and large gear 51 likewise rotate because of the connection between these parts as hereinbefore described. When the crank or handle is released the parts automatically 40 lock as the spring 48 bearing against one of the pins 43 acts to move the driving member 42 into its first position whereby its teeth 45 will engage the teeth of the fixed member 39, the part 37 being also forced back into 45 its normal position shown in Fig. 2. For 50 all practical purposes the driven member 46 and pinion 50 may be considered one part, they being constructed of two parts merely for convenience of manufacture.

The gear 51 is fixed to a shaft 52 provided with a flange 53 acting as a stop to prevent a longitudinal movement of the gear thereon. One end of said shaft 52 is hollowed out as at 54, this end of the shaft 55 being supported by a depressed support 55 pressed inwardly from the metal of the plate 4 and entering the hollowed out portion 54. The other end of the shaft is mounted in an annular neck 56 pressed out 60 from the metal of the plate 3 and forming

a bearing for said shaft, a bushing 57 being preferably interposed between said bearing and shaft. The plate 3 is also provided with an annular ridge or bead 58 pressed inwardly from the plate and acting as an 70 anti-friction support slidably engaging the side of the gear 51 and adapted to prevent rocking thereof. The end of the shaft 52 is reduced and receives the sprocket 28 which is rotatable therewith and which is 75 adapted to engage a shoulder 59 on the shaft to prevent a longitudinal movement of the sprocket thereon. The numeral 60 indicates a bolt extending through the shaft and which is provided with a head 61 received by the recess 54. The opposite end of said bolt carries a washer 62 adapted to prevent removal of the sprocket from the shaft.

The plate 4 is provided with an inwardly 80 extending lug 63 cut from the metal to which one end of a counterbalancing spring 64 is secured or hooked, the other end of said spring being secured or hooked to a lug 65 on the gear 51. The spring is supported and prevented from spreading outwardly by additional lugs 66 on said gear and is prevented from too great an inward movement, which might tend to interfere with the rotation of the shaft 52, by a semi-circularly shaped ridge or head 67 pressed inwardly from the plate. The counterbalancing spring per se is old although in so far as we are aware the particular manner of mounting and holding the same in proper 90 position as shown and described is new. The function of the spring is to assist in the raising of the window, the spring being wound up by the lowering of the window.

Referring now to the operation of the 105 window controlling mechanism described herein it will be seen that when the parts are in a position of rest and no force is being applied to the manual member 31 and shaft 32, the spring 48 will cause the movable locking element 42 to be moved into 110 position to engage the teeth of the fixed clutch member 39. When rotative force is applied to the operating shaft 32 the actuator 42 is moved away from the fixed clutch 115 39, the actuator head 37 engaging against one of the side surfaces of the stop member 44^a positioned at the ends of the arcuate surfaces 44^b. Further rotation of the operating shaft 32 causes the driving member or 120 movable clutch member 42, the operated member 46, and gears 50 and 51 to be actuated with the result that the roller stud 29 and window 1 are elevated or lowered dependent on the direction of rotation of the operator. When the handle 31 is again released the spring 48 causes the movable clutch member 42 to be moved into locking engagement with the teeth of the fixed 125 clutch member 39.

This application is a division of U. S. application for Letters Patent for window regulator, Ser. No. 557,470, filed Apr. 29, 1922.

5 We claim:

1. In a window regulator, a rotatable member, an actuator for said rotatable member including a manual handle and an actuating shaft, a non-rotatable clutch member, 10 and a slidable locking member adapted for engagement with said clutch member, said locking member being automatically moved to clutching position and being moved to non-clutching position by movement of said handle. 15
2. In a window regulator, a rotatable member, means for rotating said rotatable member or locking it against rotation, said means including a manual operating shaft, 20 and a non-rotatable clutch member, a locking member surrounding said shaft and slidably relatively thereto into or out of engagement with said clutch member, a crank controlled by said operator and arranged to engage said locking member to move the same to non-clutching position. 25
3. In a window regulator, a rotatable member, means for rotating said rotatable member or locking it against rotation, said means including a manual operating shaft, 30 a non-rotatable clutch member, a locking member slidably arranged with respect to said operating shaft and having means for moving the same into engagement with said clutch member, and means controlled by said manual operating shaft for moving said locking member away from said clutch member. 35
4. In a window regulator, a rotatable member and means operatively connecting said member to said window, means for rotating said rotatable member, said means including a manual operating shaft, a fixed member, a locking member arranged for rotation with or for sliding movement with respect to said operating shaft, means tending to move said locking member outwardly with respect to said operating shaft into engagement with said fixed member, and 45 means carried by said shaft operating upon rotation of said shaft to withdraw said locking member. 50
5. In a window regulator, a rotatable member and means operatively connecting said member to said window, means for rotating said rotatable member, said means including a crank shaft, a fixed clutch member, a spring-pressed locking member mounted for rotation with or with respect to said crank shaft and movable to position to engage said clutch member, and a crank 55 formed on said crank shaft and arranged for limited pivotal movement with respect to said locking member for controlling the movements of the latter. 60
6. In a window regulator, a rotatable member and means operatively connecting said member to said window, means for rotating said rotatable member, said means including a crank shaft, a fixed clutch member, a spring-pressed recessed locking member mounted for rotation with or with respect to said crank shaft and movable to position to engage said clutch member, and a flanged crank formed on said crank shaft 70 and arranged for limited pivotal movement with respect to said locking member for controlling the movements of the latter, the flanged portion of said crank fitting within the recessed portion of said locking member. 75
7. In a window regulator, a rotatable member and means operatively connecting said member to said window, means for rotating said rotatable member, said means including a manual operating shaft, a fixed member, a locking member arranged for rotation with or sliding movement with respect to said operating shaft, a slotted driven member associated with said rotatable member for rotation therewith, a spring 80 within the slot in said driven member and engaging said locking member to move the same outwardly with respect to said operating shaft into engagement with said fixed member, and means carried by said shaft operating upon rotation of said shaft to withdraw said locking member. 85
8. In a window regulator, a lower rotatable member, a housing, a shaft mounted on said housing, an upper rotatable member mounted on said shaft, a linear member extending over said rotatable members, for transmitting motion, a gear on said shaft, a crank shaft, a pinion loosely carried thereby meshing with said gear, a fixed clutch member secured to said housing, a driving member carried by said crank shaft and adapted to lock with said fixed member and a driven member engaging said pinion and connected to said driving member by a sliding engagement. 90
9. In a window regulator, the combination with means for raising and lowering the window including a crank shaft, a crank mounted thereon and an actuator on said crank shaft, of a fixed clutch member having a toothed opening, a driving member within said toothed opening having a tooth adapted to engage the teeth of said opening and adapted to be rotated by the actuator on said crank shaft, a driven member slidably engaging said driving member and means associated with said driven member tending to move said driving member whereby its tooth will engage the teeth of said fixed member. 115
10. In a window regulator, the combination with means for raising and lowering the window including a crank shaft, a crank mounted thereon and an actuator on said 120
- 130

crank shaft, of a fixed clutch member provided with locking means thereon, a driving member supported by said actuator and provided with locking means adapted to engage said first-named locking means, a driven member slidably connected to said driving member and spring means tending to move said driving member into position wherein the aforesaid locking means will engage each other.

11. In a window regulator, the combination with means for raising and lowering the window including a crank shaft, a crank mounted thereon for rotating said shaft and an actuator carried by said shaft, of a fixed clutch member provided with locking means thereon, a driving member supported by said actuator, pins on said driving member, a driven member having slots therein receiving said pins and a spring within one of said slots engaging one of said pins.

12. In a window regulator, the combination with means for raising and lowering the window including a crank shaft, of a fixed member provided with teeth thereon, a driving member carried by said shaft and provided with inwardly projecting members having cam surfaces thereon, pins projecting from said driving member and a driven member provided with slots adapted to receive said inwardly projecting members and pins and having fingers adapted to engage the teeth of said fixed member.

13. In a window regulator, the combination with means for raising and lowering the window including a crank shaft, of a fixed member provided with teeth thereon, a driving member carried by said shaft and provided with inwardly projecting members having cam surfaces thereon, projecting means on said driving member, a driven member provided with slots adapted to receive said inwardly projecting members and having fingers adapted to engage the teeth of said fixed members, the sides of said slots being adapted to ride against the cam surfaces of said projecting members upon rotation of said shaft whereby said projecting means will engage said sides to drive the driven member and spring means acting to retain said fingers and teeth in engagement with each other.

14. A clutch for a window actuator comprising a manual operating member, a fixed clutch member, a movable clutch member and an operated member, said movable clutch member having a recess for receiving said manual operating member, the latter having an operating extension fitting within said recess and movable therein between predetermined limits for moving said movable clutch member relatively to said fixed clutch member.

15. In combination with a movable window, an actuating mechanism and clutch

therefor comprising an operating shaft, a movable locking member and an operated member loosely mounted on said shaft, means for causing said locking member and operated member to be rotated together, said means permitting bodily movement between said members, said movable locking member being provided with a plurality of recessed portions terminating in fixed stops, an actuating element supported fixedly upon said operating shaft and fitting within recess and movable between said fixed stops for controlling said movable locking member.

16. In a window regulator, an actuating mechanism and clutch therefor comprising an operating shaft, a movable locking member and a fixed locking member, said locking members having cooperating engagement portions, said movable locking element having a recess formed with a transverse wall and stop surfaces joined by arcuate portions, an actuating element secured to said operating shaft and positioned within said recess normally in engagement lengthwise with said transverse wall, the end portions of said actuating element being capable of movement around said arcuate portions into engagement with said stop surfaces.

17. In a window actuating mechanism, an operating shaft, a fixed locking member surrounding said shaft and having inwardly extending locking teeth, an operated member, a movable locking member having means for engagement with the teeth on said fixed locking member and mounted for rotation with but for bodily movement with respect to said operated member, an actuating element secured to said operating shaft and having means for engagement with said movable locking member for withdrawing the latter from engagement with the teeth on said fixed locking member by rotation of said operating shaft.

18. In a window actuating mechanism, an operating shaft, a fixed locking member surrounding said shaft and having inwardly extending locking teeth, an operated member, a movable locking member having means for engagement with the teeth on said fixed locking member and mounted for rotation with but for bodily movement with respect to said operated member, an actuating element secured to said operating shaft and having means for engagement with said movable locking member for withdrawing the latter from engagement with the teeth on said fixed locking member by rotation of said operating shaft and means for automatically moving said movable locking member into engagement with the teeth on said fixed locking member upon release of said operating shaft.

19. In a window actuating mechanism, an

operating shaft, a fixed locking member surrounding said shaft and having inwardly extending locking teeth, an operated member, a movable locking member having means for engagement with the teeth on said fixed locking member and mounted for rotation with but for bodily movement with respect to said operated members, an actuating element secured to said operating shaft and having means for engagement with said movable locking member for withdrawing

the latter from engagement with the teeth on said fixed locking member by rotation of said operating shaft and means for limiting relative rotation between said actuating element and said movable operating member in both directions. 15

Signed at New York in the county of New York and State of New York this 27th day of April A. D., 1926.

PETER JOHN KURSCHEIDT.
HARRY E. NORWOOD.
